SUPPORT FOR CAR CLEANING EQUIPMENT AND THE LIKE

Ivan J. Barber, Mississauga, Ontario, Canada, assignor to
The Allen Group Inc., Huntington Station, Long Island,
N.Y.

Filed June 12, 1975, Ser. No. 586,296

Term of patent 14 years

Int. Cl. D15—05

U.S. Cl. D15—56

Fig. 1

Fig. 2

Fig. 4

Fig. 3

FIG. 1 is a perspective view of a support for car cleaning equipment showing my new design;

FIG. 2 is a right elevational view thereof, the left elevational being identical thereto;

FIG. 3 is a top plan view thereof; and

FIG. 4 is a left end view thereof, the right end view being identical thereto.

I claim:

The ornamental design for a support for car cleaning equipment and the like, as shown and described.
